(57) CLAIM

The ornamental design for an ashtray, as shown and described.

DESCRIPTION

FIG. 1 is a top perspective view of the ashtray;
FIG. 2 is a bottom-front perspective view of the ashtray of FIG. 1;
FIG. 3 is a top view of the ashtray of FIG. 1;
FIG. 4 is a bottom view of the ashtray;
FIG. 5 is a top-back perspective view of the ashtray;
FIG. 6 is a back view of the ashtray;
FIG. 7 is a left side view of the ashtray according to the orientation of FIG. 1;
FIG. 8 is a front view of the ashtray; and,
FIG. 9 is a right side view of the ashtray.
The broken lines in the drawings depict portions of the ashtray that form no part of the claimed design.
